THE ESMOND MILLS, OF ESMOND, RHODE ISLAND, A CORPORATION OF MASSACHU-
SETTS.

SPINNING-FRAME.

1,254,738.

Specification of Letters Patent. Patented Jan. 29, 1918.

Application filed October 19, 1916. Serial No. 126,598.

To all whom it may concern:

Be it known that we, DEXTER STEVENS and GEORGE CLARKE, citizens of the United States, and residents of Esmond, in the 5 county of Providence and State of Rhode Island, have invented new and useful Improvements in Spinning-Frames, of which the following is a specification.

This invention relates to spinning means adapted for spinning covered or doubled yarns, one object of the invention being to provide devices for forming yarns having two or more components, one of which is a previously spun yarn and the other of which 15 is a roving applied thereto by the operation of the machine of the present invention. A typical product of the machine is a yarn suitable for the filling or weft of woven fabrics adapted to be gigged or brushed, such 20 as cotton blankets and the like. One purpose of our invention is to so act upon and distribute the roving with respect to the previously spun component, hereinafter referred to as the core yarn, as to provide a 25 final product characterized by improved evenness of weight per unit length and by improved adaptability to have the individual fibers raised or released from the surface of the yarn, after manufacture of the 30 covered yarn and after completion of the fabric.

Other objects of the invention are to provide a ring spinning frame adapted to apply to and double with a core yarn, a roving or 35 applied yarn subjected prior to application to a longitudinal draft of any desired magnitude. Other objects are to provide for proper relative tensions of core and applied 40 yarn and for associating the yarn and the applied yarn or roving together prior to spinning proper in a manner to secure an even distribution of the roving or applied 45 yarn with respect to the core yarn.

In the accompanying drawings,—

Figure 1 is a vertical cross-section of so 50 much of a ring spinning frame equipped with the new devices as is necessary to illustrate the invention.

Fig. 2 is a front elevation of the devices shown in Fig. 1.

Fig. 3 is a diagram illustration of the product.

Referring now to Fig. 1, the frame may 55 comprise any usual or preferred spinning devices. As illustrated, the spindle 1, whirl

2, spindle rail 3, and bolster 4, as well as the ring rail 5, ring 6, and traveler 7, may be of known ring-spinning construction and be provided with any suitable driving and cop- 60 building devices, not shown, for winding upon the bobbin 10 a cop of the finished 65 yarn of the desired form and dimensions, and be provided with a rail 11 and finger- board 12 of the usual construction. The frame comprises suitable overhead longitudinal frame members 13, 13^a, etc.

Longitudinally of the support 13, carrying 70 rolls 15 in pairs arranged to rotate in the same direction serve as supports for balls or cheeses 16 of applied roving *r*, usually a 75 loosely spun roving adapted to be freely drawn, with consequent loss of tensile strength and release of the bound-in ends of the individual fibers of which it is composed.

On a support 17 preferably formed as 80 shown of bent strips of metal conveniently attached directly to, or to bearing blocks 13^a supported by, the frame elements 13, 13^a, supports shown as pins 18 are arranged for 85 cops 19 of core yarn *y*. As shown, the supports 17 may comprise horizontal portions 20 extending transversely of the frame to accommodate in different transverse positions a sufficient series of cops 19 to supply 90 spindles 1 spaced at the usual distance apart, each with at least one yarn *y*. Preferably on the horizontal portion 20 a series of pairs of tension disks 22, one pair for each yarn *y* may be mounted.

Vertically above and a little to the rear 95 of the position of each spindle 1, the frame 100 supports, as on auxiliary hinged fingerboards 25, a series of pig-tail guides 26, one for each spindle through which yarns *y* from the cops 19 and tension disks 22 are passed, as shown.

The longitudinal frame member 13^a above each spindle 1 is provided with suitable bearing-holes for a tubular twister-head 30 100 having a whirl 31 adapted to be driven by a band 32 from a driving roll or pulleys (not shown) on a suitable longitudinal shaft (not shown). On any suitable frame member projecting lugs 13^b support concentric with said bearing holes and each twister-head 30 a depending bearing tube 32^a in which the head 30 rotates and beneath which its lower end projects as shown at 30^a.

Mounted on tube 32^a a yarn guide or grip 33 terminates in jaws 34 near the bite or nip of secondary draft rolls 40, 40. The rolls 40 may be supported, driven, and held 5 in contact by any suitable driving, saddle and bearing means, not shown.

The twister-head 30 terminates at its upper end in short pins 35, 35 distributed in any desired number around the opening of 10 the central bore therein. Supported on the frame member 13^a by adjustment screws 36 a glass or steel rod 37 serves as a guide for the applied roving *r* in relation to the plane of rotation of the pins 35, which may be 15 rounded and polished at their upper free ends.

The roving *r* is drawn off from the ball 16 by primary draft rolls 39^a, 39^b rotated by any usual means in the direction of the arrows 20 thereupon at a desired speed, which is a divisor of the peripheral speed of the drawing rolls 40 by the desired ratio to determine the extension of the roving *r* to be given between the primary draft rolls and 25 the secondary draft rolls 40, 40.

The roving *r* entering the twister-head 30 is given a false twist between the entrance of twister-head 30 and the primary draft rolls 39^a, 39^b, by the pins 35, while the core 30 yarn *y* passes down through twister-head 30 along side of and in contact with the roving *r*. The yarn *y* is combined with the roving *r* when it passes between the secondary draft rollers 40, 40.

35 The spinning operation proper taking place below the secondary rolls 40, 40, now twists the components *y* and *r* together as illustrated for one instance in Fig. 3, in such a manner as to leave the fibers of the 40 roving with but slight interlocking engagement with each other, the tensile strength of the resulting yarn *Y* shown in the same figure being almost wholly due to the core yarn *y*, which is substantially buried in 45 the roving. As usual in the art, the direction of twist for the spinning proper may be such as to harden or increase the twist of the yarn *y*. The position in the yarn *Y* of the component *y* may be varied by adjustment of the tension disks 22.

50 It will be observed that the roving and the core yarn are brought together at a point between the drawing elements and at a point after the drawing of the roving has 55 taken place, and after the false twist has been put into the roving. The above described mechanism thus makes it possible to apply a drawn roving and a core yarn one to the other, in a spinning frame which is 60 at the same time drafting the roving.

What we claim is:

1. In a spinning frame for covering yarns, spinning means in combination with means for drawing the covering component only, means for leading a core component to the 65 spinning means, and twisting means for applying the covering component to the core component operating between elements of the drawing means.

2. A spinning frame having in combination 70 spinning means, widely separated primary and secondary draft rolls, means for supplying to be drawn between said draft rolls an applied roving, and means for supplying a core yarn to contact with said applied roving only at a point relatively near to said secondary rolls, and twisting means operating on the material near the secondary draft rolls and between the primary and secondary draft rolls whereby to spin together 80 undrawn core yarn and drawn applied roving.

3. A spinning frame having in combination 85 spinning means, primary and secondary draft rolls, means for supplying directly to said secondary draft rolls a core yarn, and a twister head for applying a roving drawn between said primary and secondary rolls to the core, and delivering it to said spinning means in intimate contact with and 90 wrapped about said core yarn.

4. A spinning frame having in combination 95 spinning means, primary and secondary draft rolls, means for supplying to said secondary draft rolls a core yarn, and means for delivering an applied roving drawn between said primary and secondary rolls to said spinning means in intimate contact with said core yarn comprising a tubular 100 twister-head adapted to receive said core yarn substantially in the direction of its axis of rotation, and to receive said applied roving at an angle to said direction, and means for guiding said yarn and roving in 105 said directions.

5. A spinning frame having in combination 110 spinning means, draft rolls for drawing the roving, means for imparting a false twist to the roving being drawn, and means for combining a core yarn with the roving at a point between the draft rolls but beyond the place where the drawing and false twisting of the roving takes place, whereby to spin together undrawn core yarn and drawn roving.

Signed by us at Esmond, Rhode Island, this eleventh day of October, 1916.

DEXTER STEVENS.
GEORGE CLARKE.
